UNITED STATES PATENT OFFICE

2,166,807

ELECTRIC HEATER

Fred J. Ewald, Jr., Elmhurst, Ill., assignor to Edison General Electric Appliance Company, Inc., Chicago, Ill., a corporation of New York

Application April 26, 1938, Serial No. 204,331

7 Claims. (Cl. 201—64)

This invention relates to electric heaters and the like, and it has for its object the provision of improved terminal structure in heaters of this type having means for sealing and protecting the terminals of the heater.

This invention is particularly applicable to electric heaters of the sheathed type wherein a resistance conductor is enclosed by an outer metallic protective casing and is embedded in a heat-conducting, electrically-insulating material which supports the conductor in spaced relation with reference to the casing. And it contemplates the provision of improved means for sealing the terminals of electric heaters of this type whereby the heaters are rendered impervious to moisture, oil, gas, and like fluids.

In accordance with this invention in one form thereof, each terminal of the heater is surrounded with a sleeve-like body formed of some suitable electrically-insulating material, such as lava or porcelain. This body is arranged in spaced relation both with the terminal of the heater and with the sheath. And interposed within the spaces between the sleeve and the terminal, and the sleeve and the sheath is a vitreous mass of sealing material adhering to the surfaces of the terminal, the sleeve and the sheath with fluid-tight joints. A cup-like protective shield, preferably formed of a non-corrosive metal, such as stainless steel, is provided around the insulating sleeve and terminal; this member has a relatively small section inserted in the space between the insulating sleeve and the sheath, and this section is embedded in the vitreous sealing mass, which functions to secure the cup to the heater, and also to separate the small section both from the insulating sleeve and the sheath. Here again, the sealing mass adheres to the surfaces of the cup to have fluid-tight joints with it. In addition, the cup has a relatively large outer section flaring outwardly from the sheath and defining a protective casing both for the outer surfaces of the insulating sleeve, and also for the terminal section that emerges from the sleeve.

For a more complete understanding of this invention, reference should be had to the accompanying drawing in which Fig. 1 is a fragmentary elevation, partly in section, of an electric heater arranged in accordance with this invention; Fig. 2 is an enlarged sectional view taken through one terminal end of the electric heater of Fig. 1; and Fig. 3 is a fragmentary elevation in section illustrating my invention as applied to a hotplate of an electric range, the figure being drawn to a reduced scale.

Referring to the drawing this invention has been shown in one form as applied to a helical-coil sheathed electric heating unit of the type described and claimed in the United States patent to C. C. Abbott, No. 1,367,341, dated February 1, 5 1921. As shown, the heating unit comprises a helical resistance conductor 10 embedded in a compacted mass of powdered heat-refractory, electrically-insulating material 11 which supports the conductor in spaced relation with reference to 10 an outer metallic protective sheath 12. The insulating material 11 may be any suitable substance, but preferably will be formed of powdered magnesium oxide. The resistance conductor 10 has its two ends secured to terminals 13 and 13a 15 projecting from the opposite ends of the sheath, as shown.

In order to render the terminals absolutely impervious to the leakage of fluids into the sheath, each terminal is surrounded with a body 14 (only 20 25 shown in Fig. 2) formed of some suitable fluid-impermeable electrically-insulating material, such as lava or porcelain. Each insulating body is provided with a centrally arranged aperture 15 so that it 25 may be threaded over its terminal, and each is provided with a relatively small section 16 that is introduced into the associated end of the sheath, as shown in Fig. 2. Moreover, it is provided with an enlarged outer flange-like head section 17 30 which overhangs the end of the sheath, as shown. The two sections 16 and 17 preferably will be and as shown are formed integrally with each other.

The centrally arranged aperture 15 is somewhat larger than is the outside diameter of the 35 terminal 13, and the outside dimensions of the inner extension 16 are somewhat smaller than the inside dimensions of the sheath so that spaces are provided between the insulating member 14 and the terminal, and between this member and the 40 sheath.

Preferably, the end section 12a of the sheath that receives the portion 16 of the insulating sleeve will taper or flare outwardly as shown, and the inner section 16 of the sleeve 14 will have a 45 complementary taper.

A relatively large cup-shaped protective shield 18 is provided to protect the insulating sleeve 14 and also the terminal 13, this member having a relatively large semicircular section 19 whose side 50 walls flare outwardly from the end of the sheath, and a relatively small inner tapered section 20 interposed between the tapered section 16 of the sleeve 14 and the tapered end wall section 12a of the sheath. The section 20 of the shield 18 is 55

spaced both from the section 16 of the sleeve and the tapered wall section 12a.

The inner section 16 of the insulating sleeve 14, and the inner section 20 of the cup 18 are embedded in a sealing mass 21 of a suitable vitreous material, such as a suitable lead glass. As shown, the vitreous mass 21 completely fills the annular space between the sleeve 14 and the terminal, the space between the section 16 of the sleeve and the section 20 of the cup, and also the space between the section 20 of the cup and the sheath. Preferably, the sealing material also will be interposed between the overhanging flange 17 of the member 14 and that section of the cup immediately next to it, as indicated by the numeral 22.

The mass of glass 21, 22 forms fluid impervious joints with the surfaces that it engages of the terminal 13, the insulating sleeve 14, the section 20 of the cup, and the sheath. The glass preferably will have a relatively high electrical resistance at the operating temperatures of the heating unit; and preferably, it will have substantially the same thermal coefficient of expansion as the terminal, the cup and the sheath, as well as of the insulating sleeve 14.

In making the terminal sealing structure, it will be understood that after the resistance conductor 10 and its terminal have been mounted within the sheath 12 and insulated therefrom by the compacted layer 11, a small section of the insulating material 11 will be removed from the terminal end of the sheath to provide space for the insulating sleeve 14, the cup section 20 and the sealing glass 21. Then the cup 18 and sleeve 14 will be threaded on the terminal, and then the space which has been provided by the removal of the insulating material 11 will be filled with the vitreous sealing material, preferably in powdered form. The assembly, including the sheath 12 and powdered vitreous glass, is then heated until the glass is molten. The sleeve 14 and the cup 18 are then pushed down on the terminal into the glass to force the glass up around the terminal and around and about the section 16 of the sleeve 14 and the section 20 of the cup, as shown in Fig. 2. When the glass cools, a seal is produced which is substantially water and air-tight.

The terminal structure of this invention, while it has more general application, is particularly applicable to hotplates for electric ranges and the like wherein the terminal sections of the heater are directed downwardly from the cooking surface. One hotplate of this type is described and claimed in the copending application of J. C. Sharp, Serial No. 187,416 filed January 28, 1938, and assigned to the same assignee as this invention. This hotplate is shown in Fig. 3, and as there shown, it is provided with the terminal structure of this invention. As shown, the terminal ends of the sheath are directed downwardly from the heating surface 23. The downturned terminals 13 are received in a terminal housing 24 which has apertures 25 receiving the terminals (only one aperture shown). The outer end of the shield 18 preferably will be provided with a flange 26 that rests against the upper surface of the housing 24, and as shown, the housing preferably will be provided with a protuberance 27 around its aperture 25 that extends up into the cup 18. The housing 24 and its protuberance 27 preferably will be formed integrally with each other and preferably will be formed of a suitable electrically insulating material, such as a phenol condensation product. The cup 18 prevents the

entrance into the terminal of grease, drippage and the like falling from the hotplate.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by Letters Patent of the United States, is:

1. An electric heater comprising a resistance conductor, a terminal secured to said resistance conductor, a metallic sheath encasing said resistance conductor and terminal, the end of said terminal projecting from the end of said sheath, an electrically insulating sleeve within said sheath surrounding said terminal in spaced relation with said terminal and said sheath, a protective cup having a section received in the space between said sleeve and sheath and an enlarged section flaring outwardly from the sheath and insulating sleeve, and vitreous sealing material within said sheath filling the space between the terminal and insulating sleeve, and also adhering both with the sheath and the section of said cup that is received therein so as to secure the insulating sleeve and cup to the sheath.

2. An electric heater comprising a sheath, a resistance conductor within said sheath having a terminal projecting from the sheath, insulating material within the sheath between the walls of the sheath and said resistance conductor and that part of the terminal within the sheath, a mass of sealing glass within said sheath between the terminal and walls of the sheath, an electrically insulating sleeve threaded on said terminal and a protective cup for the sleeve surrounding the sleeve, and both the sleeve and cup having sections extending into the sheath and embedded in said mass of glass so that the glass separates the sleeve both from the terminal and the cup and also separates the cup from the sheath.

3. An electric heater comprising a resistance conductor, a metallic sheath encasing said conductor, a terminal for said conductor and means sealing said terminal comprising a substantially homogeneous layer of electrically insulating material between said terminal and said sheath substantially filling the space between these members but spaced from each of them, a relatively large protective cup flaring outwardly from the sheath and having a relatively small section extending into the sheath but spaced from the sheath and said layer of electrically-insulating material, and substantially homogeneous layers of glass having relatively high electrical resistivity at the operating temperatures of the heater arranged in the spaces between said terminal and insulating material and between the said small section of said cup and said insulating material and sheath.

4. The combination with an electric heater provided with a resistance conductor embedded in an insulating material enclosed by a metallic sheath and a terminal secured to said conductor and projecting from said sheath of an electrically insulating body in said sheath surrounding said terminal in substantially concentric relation therewith and with said sheath and in spaced relation with these members, said body projecting from said sheath and having a flange exteriorly of said sheath and overlapping the adjacent end of said sheath, a metallic cup having a relatively small section extending into said sheath and an

- enlarged section outside of the sheath flaring outwardly from said small section and the small section spaced both from the part of said insulating body in said sheath and from the sheath, and a 5
5. mass of sealing glass filling the spaces between the insulating body and terminal and said small cup section, and between said section and said sheath, and also between said flange and the enlarged section of said cup and adhering to all of 10
10 these members so as to have fluid-tight joints with them.
6. An electric heating unit comprising a sheath, a heating element in said sheath, a terminal for said heating element projecting from 15
15 said sheath, an insulating block having an opening in which the end of said terminal is received, and also a portion extending into said sheath, a cup-shaped shield around said terminal having a part inserted in the end of said sheath 20
20 in the space between the sheath and the portion of the insulating block that is in the sheath, and sealing material within said sheath between that part of the shield that is in the sheath and the inner walls of the sheath and said insulating block.
7. An electric heating unit comprising a sheathed heating element having a terminal end, a terminal projecting from said end, a cup-shaped shield around said terminal having a part in- 25
25 serted in the end of said sheath, an insulating block having an opening in which the end of said terminal is received, and also having a flangelike protuberance around said opening and received in said cup-shaped shield, and sealing material interposed between said flange-like protuberance and said shield and also embedding the parts of said shield and insulating block that are within said sheath.
8. An electric heater comprising a resistance 10
10 conductor, a terminal secured to said resistance conductor, a metallic sheath encasing said resistance conductor and terminal, the end of said terminal projecting from the end of said sheath, an electrically insulating sleeve within said sheath 15
15 surrounding said terminal in spaced relation with said terminal and said sheath, the section of said sheath around said sleeve flaring outwardly toward the end of the sheath, a protective cup having an enlarged part flaring outwardly from the 20
20 sheath and a relatively small part inserted in said sheath, tapered to the flare of the sheath, and spaced both from the sheath and the sleeve, and a substantially homogeneous mass of glass filling the spaces between the sleeve and terminal 25
25 and tapered section of said cup, and also the space between said tapered section and said sheath.
